UNITED STATES PATENT OFFICE.

BURT D. STEVENS, OF EVANSTON, ILLINOIS, ASSIGNOR TO MIEHLE PRINTING PRESS & MANUFACTURING COMPANY, OF CHICAGO, ILLINOIS, A CORPORATION OF ILLINOIS.

INKING ARRANGEMENT FOR PRINTING PRESSES.

1,242,259.

Specification of Letters Patent.

Patented Oct. 9, 1917.

Application filed March 9, 1916. Serial No. 83,014.

To all whom it may concern:

Be it known that I, BURT D. STEVENS, a citizen of the United States, residing at Evanston, in the county of Cook and State 5 of Illinois, have invented certain new and useful Improvements in Inking Arrangements for Printing-Presses, of which the following is a specification.

The invention has to do more particularly with a form of mounting for the ink distributing rolls whereby to afford ready access to these rolls and also to the underlying distributing and rider rolls for cleaning and other purposes.

15 The object above noted is obtained by mounting the distributing rolls on a carriage for ready movement from an operative normal position above the rider rolls to a position clear thereof, a temporary 20 clearance track being provided for the carriage, which track when not in use can be readily removed out of the way.

In order that the invention may be readily understood by those skilled in the art, a 25 preferred embodiment of the same is set forth in the following detailed description and in the accompanying drawings wherein—

Figure 1 is a top plan view showing an 30 embodiment of the invention; and

Fig. 2 is a side elevation of the same.

Obviously the invention is susceptible of embodiment in other and various constructional forms without departure from the 35 scope thereof, wherefore the drawing and description are to be understood as illustrative rather than as unnecessarily limiting the invention.

In the drawing the reference numeral 11 40 indicates generally the portion of the press for making the impression, the ink trough being shown at 12, ductor roller 13, while the inking rolls are indicated and referred to generally as comprising two sets, the ink 45 distributing rolls 14 and the set of rider rolls at 15. The two sets of rolls thus generally referred to are normally arranged in superposed relation and it is for the purpose of giving access to the lower set of 50 rolls that provision is made by the present invention for removing the upper set of rolls from normal position overlying the lower set to a position at one side thereof.

Having this object in view, the upper set 55 of distributing ink rolls, instead of being

mounted in fixed portions of the ink supporting frame at 16 are instead mounted in a carriage 17 arranged to travel by means of the wheels 18 upon a track 19, this track consisting of parallel rails constituted by the 60 upper edge of the frame 16. Normally, when in operation, the carriage is locked in position upon the frame 16 in any well known suitable way.

To accommodate the carriage and its load 65 of distributing rolls when moved from normal operative position a clearance track is provided formed of rails 20 arranged as a continuation of the rails 19 and hinged thereto at 21. The rails 20 constituting the 70 clearance track are, when in use, detachably held in parallel fixed relation by means of a latch device 22 of any well known construction.

When it is desired to gain access to the 75 set of rider rolls 15 the carriage 17 is relieved from its connection to the frame 16 and rolled to the position indicated in dotted lines in Fig. 2 upon the clearance track 20. When the purpose of its removal has 80 been accomplished, the carriage is returned with its load of ink distributing rolls to the position shown in full lines, the latch 22 is released and the rails 20 may be swung upon their hinges 21 to the position indicated in dotted lines in Fig. 1 where they 85 will be out of the way.

I claim:

1. In an inking arrangement for printing 90 presses, the combination of superposed co-operating sets of ink rolls, a carriage-mounting for the overlying set of rolls, a permanent track for the carriage in the normal position of the rolls, and a clearance track 95 connected with the permanent track for the carriage whereby the upper set can be moved clear of the lower set to afford ready access thereto, the clearance track extending to one side of the roll-supporting frame and comprising rail members each 100 forming a continuation of the corresponding rail member of the permanent track and hinged thereto for folding to an inoperative position alongside the permanent rails.

2. In an inking arrangement for printing 105 presses, the combination of superposed co-operating sets of ink rolls, a carriage-mounting for the overlying sets of rolls, a permanent track for the carriage in the normal position of the rolls, and a clearance track 110

connected with the permanent track for the carriage whereby the upper set can be moved clear of the lower set to afford ready access thereto, the clearance track extending to one side of the roll-supporting frame and comprising rail members each forming a continuation of the corresponding rail member of the permanent track and hinged thereto for folding in a horizontal plane to an inoperative position alongside the permanent rails.

3. In an inking arrangement for printing presses, the combination of superposed co-operating sets of ink rolls, a carriage-mounting for the overlying sets of rolls, a permanent track for the carriage in the normal position of the rolls, and a clearance track connected with the permanent track for the carriage whereby the upper set can be moved

clear of the lower set to afford ready access thereto, the clearance track extending to one side of the roll-supporting frame and comprising rail members each forming a continuation of the corresponding rail member of the permanent track and hinged thereto for folding in a horizontal plane to an inoperative position alongside the permanent rails, and a latch device for releasably holding the rails of the temporary track in parallel operative position.

In testimony whereof I have hereunto signed my name in the presence of two subscribing witnesses.

BURT D. STEVENS.
